Primary Examiner—James R. Largen

Attorney, Agent, or Firm—George F. Bethel; Patience K. Bethel

[57] CLAIM

The ornamental design of a syphon fitting, as substantially shown herein.

DESCRIPTION

FIG. 1 is a perspective view taken from the top, front and one side of a syphon fitting showing my new design;

FIG. 2 is an elevational view taken from the side opposite that shown in FIG. 1;

FIG. 3 is a bottom plan view thereof;

FIG. 4 is a rear elevational view thereof; and

FIG. 5 is a cross-sectional view taken on line 5—5 of FIG. 4.
